(57) **CLAIM**

I claim the ornamental design for a car console liner, as shown and described.

DESCRIPTION

FIG. 1 is a perspective view showing my new design for a car console liner.

FIG. 2 is a top view thereof.

FIG. 3 is a bottom view thereof.

FIG. 4 is a rear view thereof.

FIG. 5 is a left side view thereof.

FIG. 6 is a right side view thereof.

FIG. 7 is a front view thereof; and,

FIG. 8 is a top view thereof, shown in environmental use. The broken lines represent unclaimed subject matter and form no part of the claimed design.

The shading lines shown in the drawings represent the approximate three-dimensional contour of the design, and are not intended to indicate surface decoration.
